UNITED STATES PATENT OFFICE.

HENRY HUNGERFORD, OF BROOKLYN, NEW YORK.

IMPROVED SAFETY-ESCUTCHEON FOR LOCKS.

Specification forming part of Letters Patent No. 43,504, dated July 12, 1864.

To all whom it may concern:

Be it known that I, HENRY HUNGERFORD, of the city of Brooklyn, State of New York, have invented a new and useful Improvement in Safety-Scutcheons for Locks; and I do hereby declare that the following is a full, clear, and exact description thereof and of its manner of operation, reference being had to the accompanying drawings, and to the letters of reference marked thereon, and making a part of this specification.

My invention is an improvement in the form and construction of a device for preventing locks being picked or unlocked, consisting of the use of a slotted plate attached to the lock and passing each side of the key so as to hold it and prevent its being turned.

Figure 1 is a front view of a lock with the safety-scutcheon in proper position upon the key. Fig. 2 is a sectional view of the scutcheon-plate with the key in it. Fig. 3 is a front view of a lock, the key removed and the scutcheon-plate raised above the key-hole.

It is well known that door and other locks which lock and unlock from both sides furnish but a very imperfect protection against burglars and skillful thieves. If the key is left in the lock, it can easily be turned by nippers, and the lock be thus unlocked, while if the key is taken out of the lock an easy opportunity is offered to pick it. Generally, however, the lock cannot be picked so long as the key remains in it, or it can be picked only with great difficulty.

A device which can be easily attached to such locks, which will permit the key to remain in the lock, thus greatly lessening or removing any liability of the lock being picked, and which will effectually prevent the key being turned in the lock, and which requires no alteration in the operating parts of the lock and will not mar its appearance, is not only desirable, but a positive utility. Such a desideratum my invention secures.

Upon the face of the lock, or upon the scutcheon-plate, which generally protects the key-hole, I fix a metallic plate, A, fitting into guides or grooves b b, so that it can move up and down, and which has a slot or recess, B, taken out of the middle of it, so that the side parts can pass down on each side of the key, as shown in Fig. 1. To receive such mov-

able plate A the opposite sides of the key are flattened or grooved, as shown in Fig. 2, and at such part of the key that when it is in the lock the flattened or grooved surfaces will be in the same vertical plane with the movable plate A. The width of the slot or recess B is such as to take in the flattened or grooved part of the key, but not allow the key to be turned while such plate A is upon the key, as shown in Fig. 1.

The side of the key usually flattened or made with flat faces or surfaces in the side on which is the bit or rivet C of the key, and the side opposite thereto, so that the key, when fastened by the plate A, will be at a half-turn in the lock, and cannot therefore be forced from the outside through or out of the lock. It is not, however, absolutely necessary that such flattened or faced surfaces should be on those particular sides of the key, though it is preferable, for the reason above mentioned, that they should be, as it will be apparent that the key can neither be turned in the lock nor easily dislodged therefrom, whatever its position, so long as the plate A is in the position shown in Fig. 1. Nor will it matter whether such plate moves vertically or horizontally, or at an angle, as its action on the key will be the same. Such plate is held either above the key-hole to permit the key to be inserted, or upon the key, as shown in Fig. 1, by a thumb-screw, D, acting against the lock or the plate underneath A. Instead, however, of such thumb-screw, a spring may be fixed to the lock or back plate, which shall enter into proper niches in the back side of the plate A, holding it up or down, such spring being forced back to allow such plate to be moved by a pressure-knob. Other mechanical devices may also be used for the same purpose. The plate A may also, for neatness of appearance as well as protection, be placed behind the usual scutcheon plate.

Instead of flattening the shank of the key, it may be enlarged by side projections with flat surfaces, the slot in plate A being fitted thereto; or such projecting sides may be drilled to receive the legs of the plate A, shaped to pass into them. Other variations in form may be made, retaining the same principle of operation. In cases also where the prolonged end E of the key passes through the lock this may

be fitted to receive the plate A, and the key can then be held in the lock from whichever side of the lock it is entered.

The drawings show the application of the safety-scutcheon to "mortise-locks," so called. When applied to rim locks, the guides b b will be a part of the side plate.

A movable plate with a central slot or recess has heretofore been applied for the same purpose, but such plate has been entirely separate from the lock and fastened wholly on the outside of the lock, and held in position by two pins or screws—one at or near either end of such plate—slots being cut in each end of such plate, so that it could have motion backward and forward on such pins, and such plate being also curved a little, so as to hug the face of the lock and not be as likely to drop at the wrong time. Such arrangement and construction of plate and the manner of supporting

and confining it, when compared with my form of construction and arrangement, is greatly inferior in respect to simplicity, fixedness of position, durability, and cheapness; and with the use of my device for supporting and operating such plate the combined lock and scutcheon-plate can be constructed not only more cheaply, but more elegantly.

What I claim as my invention, and desire to secure by Letters Patent, is—

Supporting and confining the movable locking-plate A on the outer surface of the scutcheon-plate by means of the guides and grooves b b and thumb-screw D, or its equivalent, all as set forth.

HENRY HUNGERFORD.
